(57) **CLAIM**

The ornamental design for a case for electronic communications device, as shown and described.

DESCRIPTION

FIG. 1 is a front perspective view of a case for electronic communications device showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of the encircled region from FIG. 2; and,

FIG. 10 is an enlarged detail view of the encircled region from FIG. 4.

The dash-dot broken line circles in FIG. 2 and FIG. 4 delineate portions of the case for electronic communications device that are part of the claimed design and that are shown on an enlarged scale in FIG. 9 and FIG. 10.

Except for solid-line regions shown in FIG. 1 that immediately surround the interior portions of the buttons and openings, the interior of the case shown in FIGS. 1 and 3 forms no part of the claimed design.
